United States Patent Office

Des. 221,183
Patented July 13, 1971

221,183

LUMINAIRE

Mitchell Bobrick, Culver City, Calif., assignor to Holophane Company, Inc., New York, N.Y.

Filed Oct. 23, 1969, Ser. No. 19,690

Term of patent 14 years

Int. Cl. D26—03

U.S. Cl. D48—31

FIG. 1.

FIG. 2.

FIG. 1 is a top perspective view of the luminaire showing my new design;

FIG. 2 is a bottom perspective view thereof.

The side not appearing in the drawings has same design appearance as side shown.

I claim:

The ornamental design for a luminaire, substantially as shown and described.
